UNITED STATES PATENT OFFICE.

THOMAS ROBERTS, OF SAN FRANCISCO, CALIFORNIA.

SHOE OR BOOT VENTILATING DEVICE.

991,457.

Specification of Letters Patent.

Patented May 2, 1911.

Application filed February 4, 1910. Serial No. 542,142.

To all whom it may concern:

Be it known that I, THOMAS ROBERTS, a citizen of the United States, residing in the city and county of San Francisco and State of California, have invented a new and useful Shoe or Boot Ventilating Device, of which the following is a specification.

My invention relates to shoes and boots and has for its object to provide means for 10 ventilating and causing a circulation of air in the sole and beneath the foot of the wearer in order to prevent overheating, perspiration, and the evils that are productive of corns, weariness, etc.

15 Further objects and advantages of the invention will appear in the following description and the novel features pointed out in the appended claim and fully illustrated in the accompanying drawings, in which,—

20 Figure 1, is a longitudinal vertical section of a shoe or boot embodying my invention; on the line $x-x$ Fig. 2; the upper part being removed; Fig. 2 is a rear view of the heel of a shoe or boot, the upper part likewise 25 omitted; Fig. 3, is a vertical transverse section on the line $y-y$ Fig. 1; the upper part removed. Fig. 4, is a perspective view of the ventilating tube. Fig. 5, is a plan of the insole, a portion being omitted; Fig. 6, is a 30 plan of the sole showing position of the ventilating tube, and Fig. 7, is a view of the screw plug of the ventilating tube.

Similar letters of reference indicate corresponding parts in all the drawings.

35 A, represents a shoe or boot, the top part being cut away, and is provided with an air chamber or cavity D between the sole and insole, the floor of said chamber or cavity D being above the plane of the upper surface 40 of the heel proper, whereby the strength and durability of the heel B are equal to those of the shoe or boot not provided with the device embodying my invention. Said chamber or cavity D may be of any desired depth, 45 according to the requirements, the depth being regulated by the thickness of the false insole, which is arranged between the outer sole C and the usual insole H. Said cavity D being formed by the concave portion situated at the forward end of the ventilating tube E, which extends beneath the cut portion C D of the sole C at the heel portion. The insole H extends over the chamber or cavity D at an approximate front of the 50 heel B of the shoe A and thereby closes the 55

top of the same, whereby the only inlet to and outlet from said chamber or cavity D is through the bifurcated end of the ventilating tube E resting in the heel and on the lower surface of the insole H which covers 60 the chamber or cavity D of the rear end and forms part of said ventilating tube E at its forward end.

Secured to the upper surface of the sole C at a short distance from the front part of 65 the toe and inserted at the flattened end part C C, in a shallow cut, is a concaved arc shaped plate D, its sides converging at its rear end with the front part of the short ventilating tube E, which passes through the 70 bifurcated opening at D D in the heel portion of the sole C, terminating at a short distance from the ends of the same, and is suitably secured as at G, to the sole; the inner surface of the tube E being threaded on 75 its interior rear end for a short distance, to receive a screw-plug F, which is inserted from the rear of the heel B whenever it is desired to close the exterior mouth of the tube E during inclement weather. 80

The insole H forms the cover of the air chamber or cavity D, and thereby closes the top of the same, whereby the only inlet is through the tube E, which rests upon the upper part of the heel at its rear end; the 85 insole H being provided with a series of ports or openings H—H, to admit fresh air to the chamber or eject foul air from the interior of the shoe or boot A when necessary.

The device acts as an inflated cushion to 90 the foot of the wearer.

This being the construction of the device, it is apparent that in operation, the pressure of the heel of the wearer, upon the cover of the chamber or cavity D, depresses 95 said cover against the supporting walls of the concaved plate D and thus forces the air, which is contained in the chamber or cavity, through, and discharges the same beneath the arch part of the foot of the 100 wearer; it will be seen that a portion of the air contained in the chamber D will be discharged through the perforations or ports H in the insole H. When the foot of the wearer is raised as in swinging the foot 105 which is toward the rear forward, in the act of taking an advance step, the action of the suction through the ventilating tube E, elevates the cover H of the chamber or cavity D, thus holding it in contact with the 110

lower part of the foot, and the upward movement of the cover produces a partial vacuum in the chamber or cavity D and causes an inward draft of air from the rear 5 part of the shoe through the ventilating tube E to the chamber D, the air thus drawn in being again expelled when the heel is again depressed. Therefore, an alternate 10 depression and elevation of the cover D is caused during walking, thus alternately exhausting the foul air from the chamber D through the tube E in the heel of the shoe or boot A and admitting a fresh supply of air into the chamber D, and this continuous circulation 15 of air within the shoe or boot A has the effect of cooling the foot, and by preventing perspiration and the evils such as are above enumerated, also adding to the comfort of the wearer and to the durability of the material 20 forming the shoe or boot A by avoiding the hardening and consequent breaking thereof. Furthermore, the construction described provides a cushion to relieve the jar

upon the ground or floor as in taking a forward step.

I claim as my invention:

In a shoe, in combination with an inner sole having a ventilating aperture in the shank of the shoe, and an outer sole having an aperture over the heel, said aperture extending forwardly upward from the under to the upper side thereof and a conduit formed in a single piece, the rear portion of said conduit passing through said aperture in the outer sole and being tubular and the front portion communicating with said aperture in the inner sole and being trough-shaped, said conduit opening at its rear end to the atmosphere, and said outer sole extending over the rear terminal portion of 40 said conduit, substantially as described.

THOMAS ROBERTS.
